UNITED STATES PATENT OFFICE.

MAURICE TAUSSIG, OF CHICAGO, ILLINOIS.

HINGE FOR HORIZONTALLY-DISAPPEARING DOORS.

1,105,221.

Specification of Letters Patent. Patented July 28, 1914.

Application filed May 14, 1914. Serial No. 838,459.

To all whom it may concern:

Be it known that I, MAURICE TAUSSIG, a citizen of the United States, and a resident of Chicago, county of Cook, and State of Illinois, have invented certain new and useful Improvements in Hinges for Horizontally-Disappearing Doors, of which the following is declared to be a full, clear, and exact description.

This invention relates to hinges for horizontally disappearing doors of cabinets, cases, or the like, where economy of space is desirable and where a neat, attractive and ornamental exterior is to be maintained. Doors for cabinets or cases, particularly those for use as store furniture, are of light wood frame-like construction, containing a pane of glass, through which the contents of the cabinet or case are visible, and the following or door support is also of light wood construction so that much difficulty has been encountered in fastening the hinges to the door and follower, because of the tendency for the wood frame to split at the places where the screws are placed, and particularly when roughly handled, although the wood often splits when handled with ordinary care and caution.

The principal object of this invention is to provide a hinge between the door and follower, of simple, yet substantial construction, which may be screwed to the door and follower without the attendant danger of splitting the wood at the places where the screws are located. To such ends this invention consists in the several novel features hereinafter fully set forth and claimed.

The invention is clearly illustrated in the accompanying drawing, in which:

Figure 1 is an edge view of fragments of two doors, a follower, and a fragment of the cabinet showing my improved hinge applied to the door and follower; Fig. 2 is a perspective view of a fragment of the door with the hinge secured thereto; Fig. 3 is a plan of the hinge and fragments of the door and follower, and Fig. 4 is a vertical section taken on line 4—4 of Fig. 1.

Referring to said drawing, which shows one embodiment of the invention, 10, designates a fragment of an upright wall or partition of a cabinet or case; 11, a horizontal division wall secured thereto, and 12, a supporting strip secured to the upright wall and arranged to support the follower 13, to which the door 14, is hinged. Said door,

when closed, extends across the open front of the cabinet and hangs in a vertical direction; preferably it comprises a rectangular wooden frame 15, and a glass plate 16, secured therein. The strips which comprise the frame 15 usually consist of thin, narrow wooden strips, secured together at their ends; the follower also may consist of a thin, wooden strip or board. This form of construction is well known and requires no further description as far as this invention is concerned and the hinge between the door and follower, which is the subject matter of this invention, will now be described. The hinge comprises two hinge leaves, 17, 18, pivoted together as at 23, and are preferably constructed of light gage strips of metal, the leaf 17, being secured to the door by screws 19, and the leaf 18, secured to the follower by screws 20. The door is rabbeted upon its rear upper side as at 21, 22, for the reception of the leaf 17, in order that the outer side may be flush with the door. The end portion 24 of the leaf 17, is bent at right angles to its main portion 25, and extends into the recess 22, or rabbeted end of the door, and its extreme end is bent at right angle to the portion 24, to form a lip 26 of a width approximately equal to the thickness of the leaf 18. The pivot between the two leaves may conveniently comprise a rivet which extends through holes in the end portions 24, 27, of the leaves. The extreme end of the leaf 18, is in the form of a semi circle, and contacts with the side of the lip 26. Preferably the pivot is located near the lower edge of the leaf 17, so as to leave more of the lip above the pivot in order that the lip may strike against the upper edge of the leaf 18, whenever the door is swung up into position in alignment with the follower. The leaf 18, is secured to the edge of the follower 13, near its bottom and its end portion 27, projects beyond the forward edge 28, of the follower and over-laps the end portion 24, of the leaf 17, to which it is pivoted. In cabinets of this kind there may be compartments, located one above the other, and in the drawing the division wall 11 represents the bottom of the compartment above the one which is closed by the door 14, and the upper compartment has a door 14^a, the lower edge of which may extend to the bottom edge of the division wall 11. The upper edge of the door 14, practically meets the lower edge of the door 14^a, and both edges

are in the form of arcs of a circle struck from the pivot point of the door 14, as a center. The corner at the upper rear side of the door is rabbeted as at 29, and the corner 5 at the upper front end of the follower is rabbeted out as at 30, to receive the projecting front edge 31 of the door when swung into alinement with the bottom as seen in dotted lines in Fig. 1. In accordance with 10 the usual practice stops 32, 33, are provided on the follower and stationary part of the cabinet to limit the forward movement of the follower and maintain the doors in vertical alinement with each other.

15 It is to be understood that a hinge is employed at both sides of the door as usual. In operation the door is suspended from the leaf 18, and when swung up into alinement with the follower, the lip 26 strikes 20 against the upper edge of the leaf 18, thus limiting its upward swing. The door may be pushed into the cabinet between the division wall 11 and strip 12, thus leaving the front of the cabinet open for access thereto.

25 It is to be observed that because the main portion of the leaf 17, lies along the rear side of the door, the screws may be screwed into the side of the door instead of into its edge, and that the danger of splitting the 30 wood is minimized thereby.

I claim as new and desire to secure by Letters Patent:

1. A hinge comprising two hinge leaves, one leaf comprising a straight flat piece, and 35 the other leaf comprising a straight flat main portion, extending at right angles to

the other leaf, one end portion thereof being bent at right angles to the main portion and parallel with the other leaf, the two leaves having a pivotal connection at said end portion and said end portion having a right angle bent at its extreme end, forming a lip adapted to strike against the other leaf to limit movement of one leaf relative to the other leaf in one direction. 40

2. A hanger for horizontally disappearing doors, comprising a stationary, horizontally extending hinge leaf, consisting of a metal strip having screw holes in its main portion, and having an end portion formed 45 with a semi-circular end and a rivet hole co-axial with said curved end; and a companion hinge leaf consisting of a metal strip having a main portion, extending at right angles to the first mentioned leaf and 50 provided with screw holes and an end portion bent parallel to and contiguous with said end portion of the first mentioned leaf and there provided with a rivet hole registering with the rivet hole of the first mentioned leaf, the extreme end of said end portion of the second named leaf being bent to over-lie the end portion of the first mentioned leaf and strike against the same when moved parallel therewith, and a rivet 55 extending through said rivet holes for pivotally connecting said leaves. 60

MAURICE TAUSSIG.
